(57) **CLAIM**

The ornamental design for a charging station, as shown and described.

DESCRIPTION

FIG. 1 is a front elevational view of a charging station showing our new design;
FIG. 2 is a rear elevational view thereof;
FIG. 3 is a top plan view thereof;
FIG. 4 is a bottom plan view thereof;
FIG. 5 is a right-side elevational view thereof;
FIG. 6 is a left-side elevational view thereof; and,
FIG. 7 is a front, top and right-side perspective view thereof. The broken lines shown in the drawings are for the purpose of illustrating portions of the charging station that form no part of the claimed design.

1 Claim, 7 Drawing Sheets
